LABORATORY TABLE UNIT

Charles G. Wall, Bala-Cynwyd, Pa., assignor to Wood-Metal Industries, Inc., Kreamer, Pa., a corporation of Pennsylvania

Filed Sept. 21, 1966, Ser. No. 3,943

Term of patent 14 years

(Cl. D16—2)

FIG.1

FIG.2

FIG.3

FIG.4

FIG.5

FIG.6

FIGURE 1 is a perspective view of a laboratory table unit showing my new design;

FIGURE 2 is a bottom plan view thereof;

FIGURE 3 is a front elevation view thereof;

FIGURE 4 is a right side elevation view thereof;

FIGURE 5 is a rear elevation view thereof; and

FIGURE 6 is a left side elevation view thereof.

The dominant features of my design reside in the portions shown in full line. The broken line representation of the water fixture as disclosed in FIGURE 1 of the drawing has been omitted in FIGURES 3 to 6 inclusive for ease of illustration.

I claim:

The ornamental design for a laboratory table unit, substantially as shown and described.
